UNITED STATES PATENT OFFICE.

ANDREW L. ENGELS AND JOSEPH WALKER, OF BISBEE, ARIZONA.

ROCK-DRILL.

1,190,387.

Specification of Letters Patent.

Patented July 11, 1916.

Application filed July 21, 1914. Serial No. 852,300.

To all whom it may concern:

Be it known that we, ANDREW L. ENGELS and JOSEPH WALKER, both citizens of the United States, and residents of Bisbee, 5 county of Cochise, and State of Arizona, (the post-office address of each being Bisbee, Arizona,) have invented an Improvement in Rock-Drills, of which the following description, in connection with the accompanying 10 drawings, is a specification, like characters on the drawings representing like parts.

This invention relates to rock drills and is more especially concerned with means for guiding the drill bit and permitting holes 15 to be started at an angle.

Our invention will be best understood by reference to the following specification when taken in connection with the accompanying drawings of one illustrative embodiment 20 thereof, while its scope will be more particularly pointed out in the appended claims.

In the drawings: Figure 1 is a side elevation of a rock drill embodying our invention; Fig. 2 is a detailed sectional view of 25 the same on an enlarged scale on lines 2—2 of Fig. 1; and Fig. 3 is a detailed view of a modified form of fastening means for the separable guide.

Referring to the drawings and to the embodiment of our invention which we have selected for illustration, we have there shown a rock drill comprising a drill bit 4 which may be operated by any appropriate means, herein a common form of pressure fluid engine having a piston 5 working in a cylinder 6, the latter being mounted in the guide- 35 ways 7 in a shell 8, upon which it may be fed longitudinally by any usual or desired means, as, for example, a feed screw 9 hav- 40 ing a crank 10, and operating in a familiar manner which it will be unnecessary here to describe, as it forms no essential part of our present invention. The shell 8 is herein shown as reversible whereby the rock drill 45 may be employed to drill holes in any position of the machine, whether in an upward or a downward direction or in a generally horizontal direction at the will of the operator.

50 In operating rock drills of this type there is often a lateral stress on the drill bit, particularly in starting holes at an angle. Under such circumstances, it is desirable to pro-

vide a guide which shall guide the outer end of the drill bit adjacent the work, apart from 55 the guidance afforded by the drill chuck or cylinder head. To this end, we have herein provided a drill bit guide designated generally by the numeral 11, preferably mounted in fixed position with respect to the length 60 of the drill bit, and the lengthwise motion of the cylinder as the latter is fed toward or withdrawn from the work.

This drill bit guide is preferably separable,—that is to say,—it is capable of being 65 opened to permit the drill bit to be removed laterally therefrom. It is, of course, well known that drill bits are provided with enlargements at the front end and sometimes 70 at the rear end as well, the front end enlargements being for the purpose of providing the necessary cutting edges with their clearances, whereas the rear end enlargement is often in the form of a shank held 75 in a drill chuck in some appropriate manner. In order to permit a drill bit of the described character to be removed from the guide, the latter is herein composed of a pair of members 12 and 13, forming together 80 an aperture 14 in which the drill bit has a sliding fit. These members may be movably mounted in any appropriate manner whereby they may be separated to permit the removal of the drill bit, but in the present embodiment of our invention are mounted 85 respectively on pivots 15 and 16, whose axes are parallel to the axis of the drill bit. These pivots are herein in the form of shouldered studs appropriately secured to the shell 8 and provided at their outer ends with nuts 90 17 and 18, by means of which a plate 19 is secured in spaced relation to a similar plate 20 at the outer end of the shell, whereby the members 12 and 13 are permitted to turn freely on their pivots while held against 95 axial movement thereon. It will here be observed that the plates 19 and 20 are both notched to provide continuations of the grooves 7 in the shell 8.

The members 12 and 13 may be held in 100 drill bit guiding relation by any appropriate means such, for example, as a swinging bolt 21 pivoted at 22 to the member 12 and engaging the member 13 in any suitable manner. Herein both members are bifurcated. 105 The bolt is hinged or pivoted in the bifurca-

tion of one member and engages in the bifurcation of the other member, and in the form shown in Figs. 1 and 2 is provided with a nut 23 by means of which the two members 5 may be fixedly secured in drill bit guiding relation, but may be instantly disconnected and swung laterally from the position shown in full lines in Fig. 2 to the position shown in dotted lines therein. In the latter position the two members may be secured to each other by the bolt and thus locked underneath the shell out of the way during the changing of the drill bit.

If desired, the nut may be dispensed with, 15 and there may be substituted for the bolt an L-shaped member 24 provided with a head 25 having an inclined or wedge-like surface or surfaces 26, whereby the two members of the guide may be drawn toward each other 20 by simply swinging the L-shaped member into place, and giving it a light tap with a hammer, thus locking the parts in drill bit holding relation.

It will now be apparent that when the 25 rock drill is in operation and a hole is being started, the described supplemental guide will effectively guide the forward end of the drill bit and prevent the latter from becoming displaced laterally, yet the drill bit 30 may be quickly and conveniently removed and replaced by another. It will also be evident that the unlocking and opening of the drill bit guide may be accomplished without the necessity of stopping the machine and immediately locked underneath out of the way 35 during the changing of the drill steels.

While we have herein shown and described one specific embodiment of our invention for illustrative purposes, and have 40 disclosed and discussed in detail the construction and arrangement incidental to one specific application thereof, it is to be understood that the invention is limited neither to the mere details nor relative arrangement of 45 parts, nor to its specific embodiment herein shown, but that extensive deviations from the illustrated form or embodiment of the invention may be made, without departing from the principles thereof.

50 Having thus described our invention, what we claim and desire by Letters Patent to procure is:—

1. A rock drill comprising, in combination, a drill bit, means for reciprocating said 55 drill bit, a mounting upon which said means is mounted to slide lengthwise of the drill bit, and separable drill bit guiding means comprising a plurality of members pivoted to the mounting in a plane transverse to said 60 drill bit in such manner that they may severally be swung clear of said drill bit and into proximity in reversed position and means to clamp said members together in similar manner either in drill bit guiding 65 relation or in said reversed position.

2. A rock drill, comprising, in combination, a drill bit, means for reciprocating said drill bit, a mounting upon which said means is mounted to slide lengthwise of the drill bit, and separable drill bit guiding means 70 comprising a plurality of members pivoted to the mounting in a plane transverse to said drill bit in such manner that they may severally be swung clear of said drill bit into proximity in reversed position and means to 75 clamp said members together in similar manner either in drill bit guiding relation or in said reversed position, the members in such first mentioned relation together forming an opening to receive and guide the drill 80 bit.

3. A rock drill comprising, in combination, a drill bit, means for reciprocating said drill bit, a mounting provided with longitudinal grooves in which said means may 85 slide, and separable drill bit guiding members pivoted to the mounting co-operatively forming an opening to receive and guide said drill bit and means to secure said members together in drill bit guiding relation, 90 said members being arranged to be swung clear of said grooves when not in guiding relation.

4. A rock drill comprising, in combination, a drill bit, means for reciprocating said 95 drill bit, a mounting on which said means may slide lengthwise of the drill bit, and separable drill bit guiding members pivoted on the end face of said mounting to swing in a plane transverse to the bit, said 100 members co-operatively forming an opening to receive and guide the drill bit and means for clamping said members together in drill bit guiding relation.

5. A rock drill comprising, in combination, a drill bit, means for reciprocating said 105 drill bit, a mounting provided with longitudinal grooves in which said means may slide, pivots projecting from the end face of said mounting, drill bit guiding members on said pivots to swing in a plane transverse to the drill bit and co-operatively 110 forming an opening to receive and guide the same, a plate having a surface conforming to and alining with the guiding surface of said mounting, maintained outwardly of said members and means to secure said members in drill bit guiding relation said members adapted to be swung clear of 115 said guiding surface when not so secured.

6. A rock drill comprising, in combination, a drill bit, means for reciprocating said 120 drill bit, a mounting provided with longitudinal grooves in which said means may slide, pivots projecting from the end face of said mounting, drill bit guiding members on said pivots to swing in a plane transverse to the drill bit co-operatively 125 forming an opening to receive and guide the same, a plate having a surface conforming 130

to and alining with the guiding surface of
said mounting, maintained on said pivots
outwardly of said members and means to
secure said members in drill bit guiding re-
5 lation said members adapted to be swung
clear of said guiding surface when not so
secured.

In testimony whereof, we have signed our

names to this specification, in the presence of
two subscribing witnesses.

ANDREW L. ENGELS.
JOSEPH WALKER.
